UNITED STATES PATENT OFFICE.

VINCENT H. FRANCIS, OF DRUMRIGHT, OKLAHOMA, ASSIGNOR TO FRICK-REID SUPPLY COMPANY, OF PITTSBURGH, PENNSYLVANIA, A CORPORATION OF PENNSYLVANIA.

PUMP.

1,337,834.

Specification of Letters Patent. Patented Apr. 20, 1920.

Application filed June 23, 1917. Serial No. 176,558.

To all whom it may concern:

Be it known that I, VINCENT H. FRANCIS, a citizen of the United States, and resident of Drumright, in the county of Creek and State of Oklahoma, have invented a new and useful Improvement in Pumps; and I do hereby declare the following to be a full, clear, and exact description thereof.

My invention relates to pumps for oil or like wells, the object of which is to provide a simple form of pump which is adapted particularly, though not exclusively, for pumping operation by wire rope or pump-rod connection to the pumping apparatus, in which a higher rate of speed in operation may be attained as compared with the pumps now generally employed using like cable or pump-rod connections.

In wells of limited production, the pumping operation as now practised is performed at a considerable loss, the apparatus employed in pumping these wells being generally the same as used in pumping wells of greater production, and the work performed is the same in each case, but with a less volume of fluid pumped per hour in the limited producing wells. Besides the loss of time in pumping, the apparatus is subjected to abnormal strains, such as slack in the cable, due to compression in the pump chamber, causing back-lash.

My invention has special advantages adapting it for use in wells of limited production, as the pumping may be accomplished more rapidly and with little wear to the apparatus, and in which the wire-rope or rods may be maintained always taut.

The invention consists in the novel construction as hereinafter described and claimed.

In the accompanying drawings, Figure 1 is a longitudinal section of my improved pump; and Fig. 2 is an enlarged view of one of the valves employed.

The numeral 2 indicates the pump-barrel or pump - cylinder corresponding generally in its function, and in regard to its position in the well, to the ordinary working barrel of regular pumping apparatus. This cylinder is provided with the usual anchor tubing and strainer 3, and has a piston 4, which is connected to the operating cable or pump-rod (not shown) by a piston-rod 4^a which passes through a stuffing-box 5 at the upper end of the cylinder. The stuff-

ing-box is preferably frictionally seated at the coupling 6, which connects the barrel to a section of tubing 7. A solid diaphragm or wall 8 closes the lower end of the cylinder below the maximum travel of the piston 60 forming a vacuum chamber 2^a beneath the piston.

The tubing 7 may be only a section of tubing connecting with the well-tubing (not shown), and it may be the lower end of the well tubing, also the structure including this section and the barrel and the strainer section may be formed as a single member such as a casting or the like, and I do not wish to limit the form of construction to that shown and described. A fluid-by-pass 9 connects with the anchor tubing below the strainer openings at 10, and connects with the working-barrel or cylinder at a point 11 above the maximum upward travel of the piston. 75 This pipe is provided with a downwardly-seating check-valve 12 and is formed with a slip-joint connection 13.

The function of this by-pass is to admit fluid to the working-barrel of the pump on 80 the down-stroke of the piston as hereinafter described.

The fluid outlet of the barrel is at a point above the maximum upward travel of the piston, and in this instance the opening 11 85 is employed; fluid by displacement of the piston is forced through this opening and into a by-pass pipe connection 14, which communicates with the well-tubing above the stuffing-box 5. A downwardly-seating 90 check-valve 15 in this pipe closes to fluid communication between the well-tubing and the working-barrel on the down-stroke of the piston, this valve and a slip-joint connection 16 being in structure similar to the 95 valve 12 and slip-joint 13 respectively.

An enlarged view in section of the valves and the slip-joints is shown in Fig. 2. The structure of the valve forms the subject of a separate application for Letters Patent, 100 Serial No. 176,559, filed by me of even date herewith, and is illustrated with this invention only as a preferable form of construction, and I do not wish to confine my invention to any particular form of valves 105 employed, nor do I wish to limit my invention to the manner of arrangement of the by-pass connections; as is obvious, pipes may be arranged differently which would function in a similar manner, for instance, 110

the by-pass connections may be formed so that the intake and outlet pipes be separate and distinct connections, and they may be formed integrally with the pumping barrel 5 such as in a casting.

In the operation of my improved pump, on the down-stroke of the piston fluid is drawn into the chamber above the piston through by-pass pipe 9, suction being created 10 in the chamber by the piston and closing the check-valve 15 at the beginning of the piston's movement. Upward movement of the piston forces this fluid through the inlet opening of the chamber into by-pass 15 pipe 14 through check-valve 15, and into the well tubing above the stuffing-box; the check-valve 12 in pipe 9 closing at beginning of the upward movement of the piston. It will thus be seen, fluid is drawn 20 into the pump chamber and discharged therefrom only from above the piston, leaving that portion of the chamber beneath the piston unobstructed for the free downward movement of the piston, the downward 25 movement being greatly facilitated as the chamber beneath the piston formed by the wall 8 provides a vacuum chamber which effects in a manner which is well understood, a downward "pull" of the piston, and 30 by reason of which a uniform tension of the pumping cable or rods is maintained in the downward movement, thus preventing slack in the cable or rods and doing away with the necessity of employment of weights 35 and the like.

From the foregoing description it will be

seen that I have provided a simple form of pump in which the fluid displacing piston may be reciprocated as rapidly as desired and in which the pumping cable is always 40 subjected to load sufficient to prevent slack during the pumping operation, thus insuring uniform length of piston strokes and smooth pumping action.

What I claim is:

1. A pump for oil or other fluid comprising an elongated tube of substantially uniform bore divided into upper and lower chambers by means of an imperforate closure, a piston working tightly within the 50 said upper chamber and a valved by-pass communicating with the said lower chamber and also communicating with the said upper chamber above the said piston.

2. A pump for oil or other fluid comprising an elongated tube of substantially uniform bore divided into upper and lower chambers by means of an imperforate closure, a piston working tightly within the 55 said upper chamber, a valved by-pass communicating with the said lower chamber and also communicating with the said upper chamber above the said piston, and means for admitting fluid to the said lower chamber.

In testimony whereof, I the said VINCENT H. FRANCIS, have hereunto set my hand.

VINCENT H. FRANCIS.

Witnesses:

GRACE HOOTON,
MABEL HERMES.
